No. 757,829.

PATENTED APR. 19, 1904.

J. W. MONTGOMERY.
WASHING MACHINE.
APPLICATION FILED OCT. 31, 1902.

NO MODEL.

UNITED STATES PATENT OFFICE.

JAMES W. MONTGOMERY, OF OCHLOCHNEE, GEORGIA.

WASHING-MACHINE.

SPECIFICATION forming part of Letters Patent No. 757,829, dated April 19, 1904.

Application filed October 31, 1902. Serial No. 129,612. (No model.)

To all whom it may concern:

Be it known that I, JAMES W. MONTGOMERY, a citizen of the United States, residing at Ochlochnee, in the county of Thomas and State of Georgia, have invented a new and useful Washing-Machine, of which the following is a specification.

The invention relates to improvements in washing-machines.

10 The object of the present invention is to improve the construction of washing-machines and to provide a simple and comparatively inexpensive one designed for washing a large quantity of clothes and capable of enabling 15 the same to be readily handled.

20 A further object of the invention is to provide a washing-machine of this character adapted to permit water to be readily introduced into and removed from the boiler with- 25 out opening the same and capable of enabling the cover or upper section of the boiler when removed to be inverted to form a washtub.

25 The invention consists in the construction and novel combination and arrangement of parts hereinafter fully described, illustrated in the accompanying drawings, and pointed out in the claim hereto appended.

30 In the drawings, Figure 1 is a vertical longitudinal sectional view of a washing-machine constructed in accordance with this invention. Fig. 2 is a transverse sectional view. Fig. 3 is a perspective view of the cover or upper section of the boiler arranged to form a wash- 35 tub. Fig. 4 is a detail sectional view on the line 4-4 of Fig. 1.

Like numerals of reference designate corresponding parts in all the figures of the drawings.

1 designates an approximately semicylindri- 40 cal boiler having a semicylindrical cover or upper section 2 and mounted on a foundation 3, of brick or other suitable material, which forms the fire-chamber and which constitutes a furnace for heating water con- 45 tained in the boiler; but the furnace may be constructed in any other desired manner. The boiler, which is provided with a sheet-metal periphery or cylinder, may be constructed in any other desired manner, and it 50 has suitable bearings at its ends for journals

4 and 5 of a rotary cylinder 6, which is located within the boiler and which is designed to contain the clothes to be washed. The sides of the boiler are provided with upwardly-extending flanges 7, which are bent outward, and 55 the cover or upper section is provided with flanges 8, which fit within the boiler and which form tight joints, as shown in Fig. 2. The ends of the cover or upper section 2 are provided with bearing-recesses 9 to receive the 60 journals 4 and 5. Legs 10 are arranged in pairs at the ends of the upper section or cover, extend upward from the same, and are adapted to support the upper section or cover when the same is inverted and arranged, as shown 65 in Fig. 3, to form a washtub.

The rotary cylinder, which consists of a sheet-metal body portion, is provided with heads 11, having suitable openings for the reception of the inner ends 12 of the journals, 70 and the said inner ends 12 are enlarged and provided with openings 13 and sockets 14, which receive rods 15 and 16. The bar 15 ex- 75 tends through the opening 13, and the bars 16 have their inner ends fitted in the sockets 14, as clearly shown in Fig. 4. These bars form arms, which have their outer ends secured to the heads of the cylinder by suitable fastening devices 17.

The cylinder is provided with openings 18, 80 and it has longitudinal cleats 19 at its inner face to rub the clothes which are introduced into the cylinder through a hinged section or lid 20. The hinged section or lid 20 is secured in its closed position by any suitable means, 85 such as wedges 21, extending through staples 22, which pass through slots of arms or extensions 23 of the free edge of the lid or section 20, the other edge being hinged at 24, as clearly shown in Fig. 2. The cylinder is rotated by 90 means of a crank-handle 25, formed integral with one of the journals, as clearly shown in Fig. 1.

The clothes or other fabrics to be washed are soaped and placed within the rotary cyl- 95 inder. The boiler is then filled about two-thirds full with water and the fire is started in the fire-chamber. The clothes are allowed to boil about twenty or thirty minutes and are rotated within the cylinder, being rubbed by 100

the cleats thereof. The dirty water is then drawn off through a drain or discharge pipe 26, which is provided with a suitable valve 27; but any other suitable means may be employed 5 for this purpose. Clean water is then supplied to the washing-machine through a funnel 28, consisting of an approximately semi-conical shell tapered toward its lower end and communicating thereat with an opening 29 of 10 the upper section or cover near the lower edge of one end of the same. The opening 29 is arranged at the bottom of the upper section or cover when the latter is in the position illustrated in Figs. 1 and 2; but when the upper 15 section or cover is inverted, as shown in Fig. 3, to form a tub, the perforation is arranged adjacent to the upper edge of the same, so that the upper section or cover will not leak when used as a tub. The upper section or cover is 20 provided at its ends with suitable handles 30, arranged in pairs and preferably consisting of longitudinal rods extended beyond the ends of the section or cover, as clearly shown in Fig. 3. The upper section or cover when removed 25 from the lower section or body of the boiler is adapted to be arranged as shown in Fig. 3,

and it forms a tub or receptacle, and it is adapted to be readily placed on and removed from the boiler.

It will be seen that the washing-machine is 30 simple and comparatively inexpensive in construction and that it is capable of rapidly washing clothes and other fabrics without injuring them.

What is claimed is—

In a washing-machine, the combination with a boiler comprising a lower section and a removable upper section, said lower section having outturned side flanges and the upper section being provided with side bars projecting 40 beyond the ends of the upper section to form handles, said bars also serving to engage the flanges on the lower section and prevent lateral displacement of the upper section when in position.

In testimony that I claim the foregoing as my own I have hereto affixed my signature in the presence of two witnesses.

JAMES W. MONTGOMERY.

Witnesses:

J. A. MONTGOMERY,
J. W. GROWER.
